UNITED STATES PATENT OFFICE.

HENRY A. SHIPP, OF FRESNO CITY, ASSIGNOR OF ONE-HALF TO WILLIAM PERKINS HALL, OF DUBLIN, CALIFORNIA.

SHEEP-ENUMERATOR.

SPECIFICATION forming part of Letters Patent No. 292,373, dated January 22, 1884.

Application filed June 5, 1882. (Model.)

To all whom it may concern:

Be it known that I, HENRY A. SHIPP, of Fresno City, county of Fresno, State of California, have invented an Improved Sheep-5 Enumerator; and I hereby declare the following to be a full, clear, and exact description thereof.

My invention relates to a new and useful device for counting sheep or other animals; 10 and it consists in certain combinations and arrangements of devices, as hereinafter fully described, and specifically pointed out in the claims.

The object of my invention is to facilitate 15 the counting of animals which herd together in large numbers, and to insure the accuracy of the count; also, in selling a number of sheep a discussion may arise as to the accuracy of the count, and thus necessitate a re-20 count, which in the ordinary method causes delay and is scarcely more to be relied upon than the first count.

Referring to the accompanying drawings, 25 Figure 1 is a perspective view of my invention. Fig. 2 is a plan of the same. Fig. 3 is a detail of construction.

Let A represent the chute of a corral, in which but one sheep can pass at a time. B is a post beyond and in line with the center of 30 the chute, to which is hinged a dodge-gate, C, extending to and a little within the chute, so that in swinging from side to side it describes an arc the ends of which meet the end of the chute on each side, thus alternately closing or 35 opening an exit on each side of the gate. This is the ordinary form of dodge-gate used to separate and distinguish sheep. Hinged to the end of this gate, on each side, are jamb-flaps D D, diverging, as shown, and held from 40 the gate by strong springs d d. Upon each side of the chute are posts E, beyond which are others, E', between which the diverging strips F of the chute-fence are secured. To these are hinged the lever-flaps G G, held therefrom 45 by light springs g g. When the gate C is in the center, the passage between the jamb and lever flaps is too small to permit a sheep to pass; but when the gate is used as in ordinary cases—that is, turned to one side—the 50 passage between one set of jamb and lever

flaps is closed, while the other is opened sufficiently to allow the passage of the sheep; but on account of the flaps this passage is narrowed sufficiently to cause a tight squeeze. The lever-flap, having but a light spring, yields 55 easily; but when a fat sheep is passing the jamb-flap will also yield. In either case the lever-flap is pressed back, the stronger spring on the jamb-flap insuring its operation.

Let into the lever-flaps is a pin, H, the other 60 end of which is forked and contains a spring-buffer, h, as shown.

Between the posts E E', upon each side, is secured a box or casing, I, in which is journaled a horizontal shaft, J, carrying a ratchet, 65 j, and a pinion, k. This engages with a large gear, L, upon a shaft, p, the end of which carries a hand, m, moving over a dial-plate, M, upon the face of the box I. The gear L has a small projecting tooth, l, which at each revolution 70 engages with a gear, N, upon a shaft, n, the end of which carries a hand, o, moving over a second dial plate, O. Upon the box P is a spring to hold the gear N in place. These 75 constitute a simple form of indicator, the hand m registering one place upon its dial-plate at each movement of the ratchet j, and the other hand, o, registering each revolution of the first hand. One of these indicators is placed upon each side of the chute A, and the pawls 80 which operate the ratchets j should be arranged to work—the one right, the other left.

Pivoted in the box I is a lever, Q, one end of which extends upward through an enlarged opening in the top of the box, and the other 85 end is provided with or formed into a pawl. This consists of two separated and downwardly-extending legs, q, one of which is provided with a foot, q', turned at right angles. The leg of the pawl which has no foot throws the 90 ratchet forward one tooth, and the leg having the foot q' allows tooth after tooth to slip beneath it as the pawl vibrates. It is thus adapted for either side of the device without further change.

The intermediate device for transmitting the motion of the lever-flap to the indicator is an elbow-lever, R, pivoted at its bend to the fence or chute, and having one end embraced by the forked pin H and the other embracing 100

the end of pawl-lever Q. When the lever-flap G is pressed back by the passing sheep, its pin H forces the lever R to move lever Q to make one point on the indicator, as described.

5 By observing the indicator the number of sheep passed through may be seen.

Having thus described my invention, what I claim as new, and desire to secure by Letters Patent, is—

10 1. The corral-chute A and the dodge-gate C, swinging to close said chute upon each side, in combination with the swinging spring-flaps G G, hinged upon each side of the chute, indicating devices, and means for transmitting the 15 yielding of the said flaps to said indicating devices to record the number of passing animals, all arranged and operating substantially as herein described.

2. The corral-chute A and the dodge-gate C, swinging to close said chute upon each side, in combination with the swinging jamb-flaps D D, with strong springs d d, the swinging lever-flaps G G, with their lighter springs gg, indicating devices, and means for transmitting the

yielding of the lever-flaps G G to said indicating devices to record the number of passing animals, all arranged and operating substantially as herein described.

3. The corral-chute A and the dodge-gate C, operating as shown, in combination with the swinging spring jamb-flaps D D, the swinging spring lever-flaps G G, the indicating devices, consisting of the boxes I, with their ratchets j, pinions k, gears L and N, hands m and o, dials M and O, and the means for transmitting the motion of the lever-flaps G G to said indicators, consisting of the forked pins H, with their spring-buffers h, elbow-levers R, with their forked ends, levers Q, and their pawls, consisting of the legs q', said pawls engaging with the ratchets j, all arranged and operating substantially as and for the purpose herein described.

In witness whereof I hereunto set my hand.

H. A. SHIPP.
